MACHINE FOR CLEARING OUT PIPE

John O. Magruder, Los Angeles, Calif.

Application July 19, 1937, Serial No. 154,456

5 Claims. (Cl. 15—104.30)

This invention relates to machines for clearing out pipe, such as sewer pipe, water pipe, cable ducts and the like, and is an improvement on my 5 Sewer cleaning apparatus, covered by my United States Letters Patent No. 2,075,215, dated March 30, 1937, and on my Machine for clearing out pipe, disclosed in my application, filed August 5, 1936, Serial No. 94,325, now Patent No. 2,183,618.

One of the objects of the invention is to provide a machine of the character stated with improved means for holding the clearing tool wire wound securely on the reel, except at the point where the wire is directed from the reel through a pipe to be cleared by the tool on the forward end of the wire, thus enabling the reel to pay out the wire and force said tool through said pipe against considerable resistance within said pipe, and preventing such resistance from obstructing said tool in said pipe and springing 20 the wire outwardly and unwinding it from the reel.

Another object is to provide a machine of the character stated with a simplified and improved variable speed transmission for operating the reel 25 on which the clearing tool wire is wound.

Other objects and advantages will appear hereinafter.

The invention is illustrated in the annexed drawings which form a part of this specification, 30 and in which,

Fig. 1 is a longitudinal section of my invention taken on line 1—1 of Fig. 2.

Fig. 2 is a plan of my invention.

Fig. 3 is a cross section on an enlarged scale 35 of the outer portion of the reel, taken on line 3—3 of Fig. 1, illustrating the wire holding means.

Fig. 4 is an enlarged fragmentary elevation of the outer portion of the reel, as shown in Fig. 3.

Fig. 5 is a fragmentary edge view of the reel 40 looking in the direction of the arrow 5 in Fig. 1.

Fig. 6 is a cross section on an enlarged scale 45 of the outer portion of the reel taken on line 6—6 of Fig. 1.

Fig. 7 is a vertical longitudinal section taken 50 on line 7—7 of Fig. 2, illustrating certain parts of the drive means for the reel frame and reel.

Fig. 8 is a side view of one of the variable 55 pulleys for driving the reel.

Fig. 9 is a vertical longitudinal section on an 50 enlarged scale taken on line 1—1 of Fig. 2, illustrating certain parts of the drive means for the reel frame and the reel.

Fig. 10 is a cross-section similar to Fig. 3, 55 showing the reel filled with wire.

Referring more particularly to the drawings,

in which corresponding parts are designated by the same reference characters in all of the views, 1 designates a supporting frame including a base 2 and end uprights 3 and 4 upstanding from said base at the forward and rear ends respectively 5 thereof. A rotatable reel frame 5 is journaled at its forward end by means of a trunnion 6 and bearing 7, and at its rear end by means of a trunnion 8 and bearing 9, which trunnions project from the forward and rear ends respectively of 10 said reel frame and are journaled respectively in said bearings, which bearings are located in the upper ends of the uprights 3 and 4 respectively. The reel frame 5 comprises of front end crosshead 10, a rear end crosshead 11 and four 15 longitudinal connecting rods 12 connected at their ends respectively to said crossheads, the trunnions 6 and 8 projecting from said crossheads respectively. Within said reel frame 5 two pairs of oppositely disposed connecting rods 20 12 is mounted a reel 13 on a shaft 14 secured at its ends in a pair of crossbars 15, which are secured respectively to said pairs of oppositely disposed connecting rods 12. The reel 13 is formed with a hub 16, a pair of discs 17 secured 25 on said hub in spaced relation, an outer rim 18, and spokes 19 connecting said discs respectively and said rim. To the reel rim 18, around its entire circumference, are secured a plurality of 30 pairs of arcuate wire holders 20, which are positioned transversely, of said rim and extend outwardly therefrom, with the ends 21, of each of said wire holders outermost and providing a space 35 22 between said ends directly outwardly from said rim, through which space a wire 23 is introduced into said wire holders, in winding said wire on the reel 13, or is removed from said wire holders, in unwinding said wire from said reel. An arcuate wire clamp 24 is pivotally mounted at one side of the rim 18 on a shaft 25, to swing 40 between each pair of wire holders 20 to clamp the wire 23 within said wire holders, the shaft 25, on which each of said wire clamps is mounted, being secured in a pair of webs 26 on the outside of the pair of wire holders 20 between which the 45 wire clamp 24 swings. The pivot shafts 25, of the wire clamps 24 of adjacent pairs of wire holders 20, are located at opposite sides of the reel rim 18, whereby the wire clamps of the respective pairs of wire holders are pivoted alternately at one side and at the other side of said reel rim, to clamp the wire from opposite sides of the reel rim at short distances apart around the reel rim, to hold the wire wound firmly on the reel, so that it cannot slip off either side of 50 55

the reel through the openings 22 between the outer ends of the wire holders 20. From the hub of each wire clamp 24 extends a weighted arm 27, outside of the pair of wire holders 20 between which said wire clamp extends, and on the outer end of said arm is secured a weight 28 which is heavy enough to swing said wire clamp inwardly between said pair of wire holders to hold the wire, under centrifugal force during rotation of the reel 13. A spring 29 is coiled in two coils 30 around the outer portions of each pivot shaft 25 beyond the wire-holder webs 26, respectively, in which said shaft is secured, and said spring is formed with a member 31 connecting the inner ends of said coils 30 and extending across the outer edge of the weighted arm 27 of the wire clamp 24 which is pivoted on said shaft, while the outer ends 32 of said coils engage the inner side of the reel rim 18, and hold said wire clamp 24 within the pair of wire holders 20, between which said clamp swings, in clamping position upon the wire 23 wound upon the reel 13, within said wire holders, whereby the wire 23 is clamped upon the reel 13 within the wire holders 20.

On the reel-supporting frame 5, forwardly of the reel 13, are mounted a pair of cams 33 at opposite sides respectively, of the reel wire holders 20, said cams being respectively secured on arms 34, which are secured on a pair of rods 12, of the reel frame 5, at opposite sides respectively of said reel. A guide 35 extends from between said cams forwardly within the reel frame 5 for guiding the wire 23 from the reel 13, or onto the reel, when the reel is rotated on its shaft 14, for unwinding the wire from the reel, or for winding the wire upon the reel. Said guide comprises a guide plate 36 and a guide tube 37 extending forwardly from said plate through a sleeve 38, from which sleeve extend a pair of supporting arms 39 secured at their outer ends respectively to a pair of rods 12 of the reel frame 5 at opposite sides of the reel 13 whereby the guide 35 is mounted upon said reel frame. The guide plate 36 is positioned so as to pass successively through the wire holders 20 and to close the spaces 22 successively between the outer ends of said wire holders, as the reel 13 is rotated. The forward end 40 of the guide tube 37 extends to within a short distance of the rear end 41 of a tubular guide shaft 42, which shaft is journaled in the forward trunnion 6 of the reel frame 5, and extends through the front and rear ends of said trunnion and rearwardly through the front cross head 10 of said reel frame. The wire 23 is guided from the reel 13 through the openings 22 between the outer ends of the wire holders 20, by the guide plate 36, and extends through and is guided by the guide tube 37 into the rear end 41 of the tubular guide shaft 42, through which shaft the wire extends and by which the wire is guided forwardly beyond the machine, there being a clearing tool 43 secured on the forward end of said wire beyond the forward end of said tubular guide shaft. On the rear end of the tubular shaft 42, within the forward end of the reel frame 5, is secured a pinion 44 in mesh with a gear 45 secured on the forward end of a shaft 46 journaled near its forward and rear ends in bearings 47 and 48 respectively, which bearings are mounted, respectively, on cross bars 49 and 50 secured to a pair of the connecting rods 12 of the reel frame 5 at one side of the reel 13. On the rear end of the shaft 46 is secured a beveled

pinion 51 in mesh with a beveled gear 52 secured to the outside of the adjacent reel disc 17.

On the forward conical end 53 of the forward trunnion 6 of reel frame 5 is secured a grooved pulley 54 by means of a nut 55 which is threaded on said end of said trunnion, as at 56 and engages the forward side of said pulley, said pulley being also keyed on said trunnion by a key 54'. A brake 57 is mounted at the rear side of the pulley 54 for application to said pulley for controlling rotation of the reel frame 5 in the manner hereinafter more fully described. The drum 58 of the brake 57 is secured to the rear side of the pulley 54, while the brake disc 59, on which the brake shoes 60 are mounted, is bolted to one end of a hub 61, surrounding the trunnion 6 and rotatably mounted thereon, by means of a ball bearing 62. The cam arm 63 of the brake is mounted on the disc 59 and the brake is operated by suitable operating means 64 connected to said cam arm.

On the forward end of the tubular guide shaft 42, forwardly of the pulley 54, is mounted a variable size pulley 65. Said pulley comprises a pair of interconnected circular pulley members 66 and 67. The member 66 of said pulley comprises a hub 68, a belt engaging annulus 69 and a connecting annulus 70 connecting the inner edge of said belt-engaging annulus and the outer edge of said hub, said connecting annulus being inclined outwardly from said hub toward the pulley member 67 and said belt-engaging annulus being inclined from said connecting annulus outwardly with relation to pulley member 67. Said pulley member 66 is formed with a plurality of radial slots 71, which extend from the hub 68 outwardly through the connecting annulus 70 and through the belt engaging annulus 69 for a portion of its width, said slots 71 forming radial spokes 72 therebetween in said pulley member 66. The pulley member 67 comprises a hub 73, a belt-engaging annulus 74, and a connecting annulus 75 connecting the inner edge of said belt-engaging annulus and the outer edge of said hub, said connecting annulus being inclined outwardly from said hub toward the pulley member 66 and said belt-engaging annulus being inclined from said connecting annulus outwardly with relation to pulley member 67. Said pulley member 67 is formed with a plurality of radial slots 76, which extend outwardly from the hub 73 through the connecting annulus 75 and through the belt-engaging annulus 74 for a portion of its width, said slots 76 forming radial spokes 77, therebetween, in said pulley member 67. The slots 71 of the pulley member 66 are positioned to receive the angular spokes 77 in the connecting annulus 75 and belt-receiving annulus 74 of the pulley member 67, while the slots 76 of the pulley member 67 are positioned to receive the angular spokes 72 in the connecting annulus 70 and belt-receiving annulus 69 of the pulley member 66, whereby the spokes 72 of the pulley member 66 are caused to interlock with the spokes 77 of the pulley member 67, so that the pulley members 66 and 67 will rotate together. The hub 68 of the pulley member 66 is fitted on the tubular guide shaft 42 and is bolted to an annular external flange 78 on said shaft by bolts 79 adjacent the outer end of the forward trunnion 6 of the reel frame 5. The hub 73 of the pulley member 67 is fitted on a sleeve 80, slidably mounted on the tubular guide shaft 42, and is bolted to an external annular flange 81 on the inner end of said sleeve by bolts 81' so that said pulley member 67 will 75

- slide with said sleeve on said shaft toward or away from the pulley member 66. A collar 82 is secured on the outer end of the tubular guide shaft 42 and a coil spring 83, surrounding said shaft and the pulley sleeve 80, is interposed between said collar and the hub 73 of the pulley member 67, which spring urges said pulley member toward the pulley member 66 and, the movement of the pulley 67 toward the pulley 66, under the influence of said spring, being limited by the engagement of the spokes 72 of the pulley member 66 with the outer ends of the slots 76 of the pulley member 67 and the engagement of the spokes 77 of the pulley member 67 with the outer ends of the slots 71 in the pulley member 66, in which position of the pulley members 66 and 67, the V-shaped belt groove 84 in the periphery of the pulley 65 is increased to its maximum diameter.
- 20 At one side of the reel frame 5 is journaled a drive shaft 85, in bearings 86 and 87, the bearing 86 being mounted in the forward end upright 3 of the frame 1 and the bearing 87 being mounted on the upper end of a standard 88 secured to the base 2 of said frame, forwardly of said upright. On said drive shaft between its bearings, are mounted drive pulleys 89 and 90. A belt 91 extends over the pulleys 89 and 54 and a belt 92 extends over the pulleys 90 and 65. The pulley 89 is normally clutched to the drive shaft 85 by a spring-actuated clutch 93. The pulley 90 is a variable diameter pulley of the same construction as that of pulley 65, and the above description of pulley 65 applies to pulley 90, except that 35 a sleeve 94, slideable on the drive shaft 85, is formed integral with the hub 73 of the member 67 of pulley 90. The hub 68 of the member 66 of pulley 90 is bolted, by bolts 95 to an external flange 96 on the drive shaft 85. The clutch disc 97 of clutch 93 is secured on an annular flange 98 on the rear end of a clutch sleeve 99 slideable on the drive shaft 85, the inner end of which sleeve is held against the flange 96 on said shaft by the springs 100 of said clutch, which spring 40 bears at one end against the disc pressure ring 101 and at its other end against the casing 102 of said clutch which casing is secured at its inner end to one side of the pulley 89 by bolts 103 which extend through an external flange 104 on 45 said end of said casing and through the radii wall 105 of said pulley to hold said flange against said wall. The pulley 89 is rotatably mounted on the drive shaft 85 by means of a ball bearing 106 which is interposed between the hub 107 of said 50 pulley and said drive shaft, the inner race 108 of said ball bearing being slideable on said drive shaft to allow the pulley 89 to be moved into or out of engagement with the clutch disc 97 in the manner hereinafter more fully described. On 55 the inner side of the clutch casing 102 are pivoted the clutch fingers 109, at 110, the outer ends of which fingers engage inturned lugs 111 outstanding from the clutch-disc pressure ring 101, while the inner ends of said fingers engage 60 the external flange 112 on the inner end of the clutch-operating sleeve 113 slideable on the drive shaft 85. A shaft 114 is journaled in bearings 115 on the upright 3 of the main frame 1, and a fork 116 is secured on one end of said shaft, while 65 70 a clutch-operating arm 117 is secured on the other end of said shaft, said fork straddling the sleeve 113 and engaging the flange 112 of said sleeve, so that when said clutch-operating arm 117 is swung counterclockwise (Figs. 2 and 7) said fork 116 engages the sleeve flange 112 and 75 forces said flange and the sleeve 113 inwardly, whereupon said flange swings the clutch fingers 109 counterclockwise and the outer ends of said fingers, engaging the lugs 111, move the disc-pressure ring 101 outwardly and relieves the 5 pressure of said ring from the clutch disc 97, while the inward pressure of said sleeve flange 112 against said fingers 109 is transmitted through said fingers, their pivots 110 and the clutch casing 102 to the pulley 89, whereupon 10 said pulley is moved inwardly away from the clutch disc 97, the inner race 108 of the pulley ball bearing 106 sliding with the pulley on the drive shaft 85, and the pulley 89 is unclutched from said drive shaft. Upon releasing the 15 clutch-operating arm 117 the clutch springs 100 force the clutch casing 102 and the pulley 89 outwardly and the disc pressure ring 101 inwardly against the clutch disc 97, whereupon the clutch disc is clamped against the radii wall 105 20 of the pulley 89 and said pulley is clutched to the drive shaft 85.
- 25 On the outer end of the sleeve 94 of member 67 of pulley 90 is turnably mounted a collar 118 by means of a ball bearing 119, which collar is 25 provided with an annular groove 120 in which is turnably fitted a ring 121 to which is pivotally connected at 122 the upper ends of a fork 123, which is secured at its lower end on a shaft 124 journaled in bearings 125 and 126 on the standard 88 and frame base 2 respectively. An operating arm 127 is secured on one end of the shaft for moving the member 67 of pulley 90 toward or away from the member 66, through the medium of the shaft 124, fork 123, ring 121 and collar 118, for increasing or decreasing the diameter of the belt groove 84 of said pulley 90.
- 30 The drive shaft 85 is coupled at its rear end by a coupling 128 to the forward end of the crank shaft 129 of an automobile engine 130 mounted 30 on the base 2 of the main frame 1, whereby said drive shaft is driven by said engine. The engine 130 is controlled by its clutch, indicated at 131, and transmission 132.
- 35 The operation, uses and advantages of my invention are as follows:
- 40 The machine is first suitably positioned and the clearing tool 43 is inserted into the end of a pipe to be cleared out. The engine is started and the drive shaft 85 and pulleys 89 and 90 are rotated by the engine shaft, the clutch 93 being 45 in its normal operative position clutching the pulley 89 to said drive shaft 85. Through the belt 91 the pulley 89 rotates the pulley 54, trunnion 6 and the reel frame 5 together with the 50 reel 13, which rotates the wire 23 and the clearing tool 43. Through the belt 92 the pulley 90 rotates the pulley 65, guide shaft 42, pinion 44, gear 45, shaft 46, bevel pinion 51, bevel gear 52 and the reel 13 on its shaft 14, whereupon the rotating wire 23 is unwound from said reel through the guide 35 and tubular guide shaft 42, the wire 55 clamps 24 being swung away from the wire and above the guide plate 36 by the engagement of the clamp weights 28 by the cams 33 as the wire 60 leaves the reel and passes through the guide tube 37, and the rotating clearing tool 43 is projected by the unwinding wire through said pipe to be cleared, and said pipe is thereby cleared out 65 by said tool.
- 70 The speed at which the clearing tool 43 is advanced through the pipe to be cleared may be varied by swinging the operating lever 127 of the pulley-varying means to move the member 67 of the pulley 90 toward or away from the mem- 75

ber 66, to vary the depth and diameter of the pulley belt groove 84, so that as the diameter of the belt groove of said pulley is increased or decreased by said pulley-varying means the diameter of the belt groove 84 of the pulley 65 is conversely decreased or increased automatically, by the changing position of the belt 92 on said pulleys, the spring 83 yielding to allow the member 67 of pulley 65 to be moved away from the member 66 of said pulley, for reducing the diameter of the belt groove of said pulley, and said spring expanding to move the member 67 of said pulley towards the member 66 for increasing the diameter of the belt groove.

15 Decrease of the diameter of the belt groove of the pulley 90 and increase of the diameter of the belt groove of the pulley 65, causes the pulley 65 and the reel 13, through its driving mechanism from said pulley, to be rotated slower by the engine, and consequently the wire 23 is unwound faster from the reel and the clearing tool 43 is advanced at a faster speed by said wire through the pipe to be cleared.

Increase of the diameter of the belt groove of pulley 90 and decrease of the diameter of the belt groove of pulley 65, causes the pulley 65 and the reel 13, through its driving mechanism from said pulley, to be rotated faster by the engine 30, and consequently the reel is rotated backwardly 20 and the wire 23 is pulled backwardly and wound upon the reel and the clearing tool 43 is pulled backwardly by said wire through the pipe to be cleared.

The advancement of the clearing tool 43 through the pipe to be cleared is effected when the pulley 65 is rotated at a slower speed than the trunnion 6 and the reel frame 5. When the pulley 65 and its shaft 42 are rotated at the same speed as the trunnion 6 the reel 13 is not rotated on its shaft 14 and consequently the wire 23 and tool 43 are neither advanced forwardly nor drawn backwardly by the reel. When the pulley 65 and its shaft 42 are rotated faster than the trunnion 6 and the reel frame 5, the reel 13 is rotated backwards, or clockwise as considered in Fig. 1, through its driving mechanism from said pulley 65, and the wire 23 and clearing tool 43 are drawn backwardly by the reel.

50 The pulley varying means, operated by lever 121, and the pulleys 90 and 65 constitute a reversing means for reversing the longitudinal movement of the wire 23 and tool 43 as well as a means for varying the speed of the longitudinal movement of the wire and tool inasmuch as the reel may be caused to rotate backwardly by varying the diameter of the pulley 90 and 65 relatively by the pulley varying means.

55 By disengaging the clutch 93 and releasing the pulley 89 from the shaft 85, and by applying the brake 57 to the pulley 54, the rotary reel frame 5 is brought to rest so that the reel 13 will be rotated backwardly, by the engine 130 running in its forward direction, to wind the wire 23 on the reel and pull the wire and the tool out of a pipe without rotating the wire and tool. With the clutch 93 disengaged and the brake 57 applied, so that the reel frame 5 is brought to rest, reversal of the engine 130, by reversing the gears of the engine transmission 132, will cause the reel to be rotated on its shaft 14 to unwind the wire 23 from the reel and project the tool and wire forwardly into a pipe, without rotating the wire and tool.

I claim:

75 1. A machine as disclosed comprising a sup-

porting frame, a reel mounted on said frame to be rotated on its transverse axis, a wire wound on said reel, a guide for guiding the wire from the reel, means for guiding the outer portion of said wire with a tool thereon to perform work, 5 a plurality of clamps on opposite sides of said reel for clamping the wire from both sides of the reel upon said reel, and means for releasing said clamps from the wire as it is guided from the reel by said guide.

2. A machine as disclosed comprising a supporting frame, a reel mounted on said frame to be rotated on its transverse axis, a wire wound on said reel, a guide for guiding said wire from said reel, means for guiding the outer portion of 15 said wire with a tool thereon to perform work, a plurality of clamps for clamping the wire on the reel alternately from opposite sides of the reel, and means for releasing said clamps from said wire as it is guided from the reel by said 20 guide.

3. A machine as disclosed comprising a supporting frame, a reel, means for revolvably mounting said reel on said supporting frame, a wire wound on said reel, means on the periphery of 25 said reel open at the outer radial sides thereof to restrain axial shifting of said wire, a plurality of clamps on the periphery of said reel for clamping said wire wound on said reel, a guide for guiding the wire unwound from said reel through 30 the open outer sides of said wire restraining means, said guide including a guide plate, positioned to pass through said wire restraining means and to form a closure for the outer open 35 sides thereof, as said wire holders travel past said guide plate and said wire is unwound from the reel under said guide plate, means for swinging said wire clamps outwardly away from the wire in said wire holders and over the side edges of said guide plate to escape said plate, as said 40 wire clamps travel past said guide plate while the wire is unwound from said reel.

4. A machine as disclosed comprising a supporting frame, a reel, means for revolvably mounting said reel on said supporting frame, a wire 45 wound on said reel, means on the periphery of said reel open at the outer radial sides thereof to restrain axial shifting of said wire, a plurality of clamps mounted to swing alternately from opposite sides, respectively of the reel over the wire 50 wound on the reel within said wire restraining means, for clamping the wire on the reel, a guide for guiding the wire unwound from said reel through the open outer sides of said wire restraining means, said guide including a guide 55 plate positioned to pass through said wire restraining means and to form a closure for the outer open sides thereof, as said wire holders travel past said guide plate, and means for swinging said wire clamps outwardly away from the wire in said wire restraining means and over the side edges of said guide plate to escape said plate, as said wire clamps travel past said guide plate while the wire is unwound from said reel.

5. A machine as disclosed comprising a sup- 65 porting frame, a rotary reel frame, trunnions on the ends respectively of said reel frame, bearings on said supporting frame in which said trunnions are respectively journaled, a reel journaled in said reel frame transversely thereof, a wire 70 wound on said reel, means on the periphery of said reel open at the outer radial sides thereof to restrain axial shifting of said wire, a plurality of clamps mounted to swing from opposite sides of the reel over the wire wound on the reel within 75

5 said wire restraining means, for clamping the wire on the reel, a hollow guide shaft journaled in one of said trunnions, a guide for guiding the wire unwound from said reel through the open sides of said wire restraining means, into said hollow guide shaft, said guide including a guide plate positioned to pass through said wire restraining means and to form a closure for the outer open sides thereof, as the wire restraining means travel past

10 said guide plate, means for swinging said clamps

outwardly from the wire on the reel in said wire restraining means and over the side edges of said guide plate to escape said plate, as said clamps travel past said guide plate while the wire is unwound from the reel, means for rotating said reel frame on its trunnions, means for rotating said hollow guide shaft, and means whereby said reel is rotated on its axis in said reel frame from said hollow guide shaft.

JOHN O. MAGRUDER. 10
